(57) **CLAIM**

The ornamental design for a body of microscope, as shown and described.

DESCRIPTION

FIG. 1 is a front, top and right side perspective view of a body of microscope, showing our new design;

FIG. 2 is a front elevational view thereof;

FIG. 3 is a top plan view thereof;

FIG. 4 is a right side elevational view thereof;

FIG. 5 is a rear elevational view thereof;

FIG. 6 is a left side elevational view thereof;

FIG. 7 is a bottom plan view thereof; and,

FIG. 8 is a reference perspective view thereof, showing the state of use.

The broken line showing of the microscope in FIG. 8 is for illustrative purposes only and forms no part of the claimed design.
